FOREIGN PATENT DOCUMENTS

GB 2 056 348 3/1981

Primary Examiner—Philip S Hyder*Assistant Examiner*—Randall H Gholson(74) *Attorney, Agent, or Firm*—McKee, Voorhees & Sease, P.L.C.(57) **CLAIM**

The ornamental design for a slim profile wrench, as shown and described.

DESCRIPTION

FIG. 1 is a perspective view of the slim profile wrench of the present invention.

FIG. 2 is a top plan view of the wrench.

FIG. 3 is a bottom plan view of the wrench.

FIG. 4 is a side elevation view of the wrench, with the opposite side being identical; and,

FIG. 5 is an end elevation view of the wrench, with the opposite end view being identical.
